(57) **CLAIM**

The ornamental design for an aircraft cockpit table, as shown and described.

DESCRIPTION

FIG. 1 is a front perspective view of an aircraft cockpit table showing our new design in a cockpit of an airplane; FIG. 2 is a top perspective view thereof; FIG. 3 is a top view thereof; FIG. 4 is a bottom view thereof; FIG. 5 is a front view thereof; FIG. 6 is a back view thereof; FIG. 7 is a first side view thereof; FIG. 8 is a second side view thereof; and, FIG. 9 is a perspective view thereof with the aircraft cockpit table in a stowed position. The broken lines illustrate structure and environment that form no part of the claimed design.
